US00D979081S

(12) **United States Design Patent** (10) Patent No.: **US D979,081 S**
Xu (45) Date of Patent: **** Feb. 21, 2023**

(54) **COLD AND HOT COMPRESSION
SHOULDER PROTECTOR**

(71) Applicant: **WUHAN PAKCARE
BIO-TECHNOLOGY CO., LTD.,**
Wuhan (CN)

(72) Inventor: **Shouwei Xu**, Wuhan (CN)

(**) Term: **15 Years**

(21) Appl. No.: **29/798,429**

(22) Filed: **Jul. 8, 2021**

(51) LOC (14) Cl. **24-01**

(52) U.S. Cl.

USPC **D24/206**

(58) **Field of Classification Search**
